UNITED STATES PATENT OFFICE.

SIDNEY U. BARR, OF NEW YORK, N. Y.

WINDOW.

No. 891,133.

Specification of Letters Patent. Patented June 16, 1908.

Application filed March 27, 1907. Serial No. 364,780.

To all whom it may concern:

Be it known that I, SIDNEY U. BARR, a citizen of the United States, and a resident of the city of New York, borough of Brooklyn, in the county of Kings and State of New York, have invented a new and Improved Window, of which the following is a full, clear, and exact description.

The invention relates to windows, such as shown and described in the Letters Patent of the United States, No. 797,835, granted to me on August 2, 1905.

The object of the present invention is to provide a new and improved window, which is completely dustproof and air tight, and arranged to permit easy opening and closing of the sashes without danger of the sashes sticking, and to allow convenient removal of a sash for repairs or other purposes and without requiring detachment of the pane or other parts of the sash.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is an inner face view of the improvement; Fig. 2 is an enlarged cross section of the same on the line 2—2 of Fig. 1; Fig. 3 is an enlarged inverted sectional plan view of the same on the line 3—3 of Fig. 1; Fig. 4 is an enlarged inverted sectional plan view of the mullion and one of the sashes partly open; Fig. 5 is an enlarged cross section of the improvement on the line 5—5 of Fig. 1; Fig. 6 is an enlarged plan view showing the mechanism for turning a sash into an open or a closed position; Fig. 7 is a sectional side elevation of the same; Fig. 8 is an enlarged cross section of the improvement on the line 8—8 of Fig. 1; Fig. 9 is a like view of the same on the line 9—9 of Fig. 1; Fig. 10 is an enlarged sectional plan view of the mechanism for operating the sash gearing, the section being on the line 10—10 of Fig. 11; and Fig. 11 is a sectional side elevation of the same on the line 11—11 of Fig. 10.

The window, as illustrated in Fig. 1, is provided with the main sashes A, A' and the transom sashes A², A³, and the said sashes A, A', A² and A³ are center-pivoted and mounted to swing in the window frame B. For the

purpose described the sashes A, A' and A² are mounted to swing on top and bottom pivots C, C' and are adapted to be locked against accidental opening by manually controlled bolts D, preferably of the extension or Cremona type. The sash A³ is mounted on top and bottom pivots C², C³, of which the top pivot C² is adapted to be turned by an actuating mechanism under the control of the operator, the said mechanism serving to hold the sash A³ locked in an open, partly open or a closed position.

The top pivot C for each of the sashes A, A' and A² (see Fig. 8) is mounted to slide vertically in the top cross bar A⁴ of the corresponding sash and is adapted to engage a bearing B' in the cross bar B² or B³ of the window frame B. The pivot C is locked in place in either an extended or a retracted position by the use of a clamping screw E screwing in the threaded hole C⁴ or C⁵ formed in the pivot C one above the other, as plainly indicated in Fig. 8. The clamping screw E extends loosely through an enlarged transverse opening A⁵ formed in the cross bar A⁴ and the outer end of the said clamping screw E is provided with a head E' adapted to engage a seat A⁶ formed on the inner face of the corresponding cross bar A⁴. Now on unscrewing the clamping screw E the pivot C can be raised or lowered by the use of a nail or other tool, so as to move the pivot C in a vertical direction in or out of engagement with the bearing B'; by engaging the clamping screw E with either threaded apertures C⁴ or C⁵ the pivot C can be locked in its raised or retracted position.

The lower pivot C' for each of the sashes A, A' and A² (see Fig. 9) is mounted to slide vertically in the bottom cross bar A⁷ of the corresponding sash, and the bottom pivot C' for each of the main sashes A, A' is adapted to engage a bearing in the sill B⁴ of the window frame B, while the bottom pivots C', C³ for the sashes A², A³ are adapted to engage bearings in the cross bar B² of the window frame B. The bottom pivots C' and C³ are alike in construction and each is provided with a number of threaded apertures C⁶, C⁷, C⁸, adapted to be engaged by a clamping screw E², similar to the clamping screw E and having a head E³ for engagement with the bottom cross bar B³ of the corresponding sash A, A', A² and A³. Now by unscrewing the clamping screw E², the pivot C' can be readily raised by the use of a nail or other

tool, and then the pivot can be locked in a raised or disengaged position by reengaging the clamping screw E^2 with the lowermost aperture C^8 of the pivot C' .

- 5 In order to insure an easy swinging of each of the sashes A , A' , A^2 and A^3 the pivotal bottom of the corresponding cross bar A^7 rests and travels on a ball bearing (see Fig. 9), consisting of a ring F in which are held balls F' projecting beyond the top and bottom faces of the ring F , the balls being engaged at the top by a ring-shaped bearing F^2 , fitting in a recess in the under side of the cross bar A^7 , and secured to the latter by screws or the like 10 (not shown). The lower ends of the balls F' rest on a ring-shaped bearing F^3 , seated in a recess in the sill B^4 or the cross bar B^2 , the said recess being sufficiently deep to also contain the ball bearing, as plainly indicated in 15 Fig. 9. Now by reference to this figure, it will be seen that the ring F and the bearings F^2 , F^3 are concentric with the pivot pin C' (or C^3), and the latter when raised passes out of the bearing F^3 and ring F , to allow of re- 20 moving the sash at the time the corresponding upper pivot C or C^2 is retracted.

Now when it is desired to remove either of the sashes A , A' and A^2 , the sashes are held locked in a closed position by the locking bolts D , and then the operator, by removing the clamping screws E and E^2 , obtains access to the top and bottom pivots C , C' of the said sashes, to retract the same, that is, to lower the top pivot C and to raise the bottom pivot 30 C' . When this has been done, the retracted pivots can be locked in place by the corresponding clamping screws E and E^2 , after which the operator unlocks the bolts D to thus free the sash in the window frame and to 35 allow removal thereof without requiring removal of the pane or other member of the sash or window frame.

As previously mentioned, the bottom pivot C^3 of the sash A^3 is like the bottom pivot C' , but the top pivot C^2 for the sash A^3 is made square (see Fig. 5), and is adapted to slide vertically in a correspondingly shaped bearing formed in the top cross bar A^4 of the sash A^3 . This top pivot C^2 is adapted to be 40 locked in an extended or retracted position by a clamping screw E^4 having a head E^5 and similar to the clamping screws E and E^2 , so that further description of this part is not deemed necessary. The upper end of the 45 top pivot C^2 is adapted to engage a correspondingly shaped recess in the hub of a gear wheel G , mounted to turn in suitable bearings formed in the top cross bar B^3 of the window frame B . The gear wheel G is in mesh at one side with a rack G' (see Figs. 5 and 6), connected by an adjustable connecting bar G^2 with a rack G^3 in mesh with a gear wheel G^4 secured on the upper end of a shaft H journaled in suitable bearings arranged in 55 the side bar B^5 of the window frame B (see

Figs. 1, 10 and 11). A stop pin G^5 arranged on the top cross bar B^3 (see Fig. 6) limits the sliding motion of the extensible rack formed of the racks G' , G^3 and the connecting bar G^2 .

The lower end of the shaft H terminates in the sill B^4 and is provided with a worm wheel H' in mesh with a worm H^2 secured on a transversely extending shaft H^3 journaled in suitable bearings arranged on the sill B^4 . The square end H^4 of the shaft H^3 extends 75 into an enlarged aperture B^6 formed on the inner face of the sill B^4 , so as to permit convenient engagement of a turning crank with the square end H^4 , to allow the operator to turn the shaft H^3 whenever it is desired to 80 swing the sash A^3 on its pivots C^2 and C^3 .

By using connecting bars G^2 of different length, it is evident that sashes of different width can be readily accommodated without requiring a change in the construction of the 85 gear shown and described.

Each of the sashes A , A' , A^2 and A^3 when moved into a closed position interlocks with the window frame, and for this purpose the detail construction of the sashes and window frame is as follows: The cross bars A^4 and A^7 of each sash are connected with the stiles A^8 and A^9 , and each of these parts of the sash frame is formed of a frame member I and an interlocking stop member I' , the several 90 members I of a sash forming the pane frame for the reception of the pane J of glass or other transparent or translucent material. The members I and I' of each sash part are screwed or otherwise fastened together and their contacting faces are provided throughout their length with registering grooves, for the reception of a pin K made of wood or other material, and serving to render the joint between the said contacting faces of the 95 members I and I' dustproof and air tight. The window frame B has each of its individual parts, that is, the cross bars B^2 , B^3 , the sill B^4 , the side bars B^5 and B^7 and the mullions B^8 built up in the same manner, that is, 100 each window frame part is provided with an interlocking stop member I^2 bolted or otherwise secured to the window frame part mentioned, and a pin K' similar to the pin K is fitted into the registering grooves between 105 the contacting faces, to render each window frame part dustproof and air tight. The members I' and I^2 for the sash parts and the window frame parts are alike in cross section, so that a window sash and a window 110 frame can be readily and cheaply built up from but few strips of different cross sectional shapes, the strips being cut into proper length to suit the size of the window. The interlocking stop members I' for each sash 115 extend partly on the outer face of the sash and partly on the inner face of the sash, and the stop members I^2 of the window frame B are correspondingly arranged (see Figs. 1, 2 and 3), the stop members I' overlapping each 120 125 130

other at the pivots C, C' and C², C³. Thus when a sash is turned at the center pivots C, C' (or C², C³) into a closed position, then the corresponding stop members I' and I² interlock with each other.

In order to render the joint between the interlocking stop members I' and I² air tight and dustproof when the sash is closed, packings or cushions L are employed, each packings being tubular and preferably made of a piece of rubber tubing, through which extends a metallic rod L' secured by screws or other means to the corresponding member I' of the sash, as plainly illustrated in Figs. 2, 15 3 and 4. The packings L are arranged in registering rabbets or grooves formed on the contacting surfaces of the members I' and I² of the sashes and window frame, but as this construction of the packing is the same as 20 that more fully described in the Letters Patent of the United States above referred to, it is not deemed necessary to describe the same any further.

Although I have shown the parts of the 25 sash frame and window frame of tubular metal, it is evident that I do not limit myself to the use of metal, as wood or other materials may be substituted.

Having thus described my invention, I 30 claim as new and desire to secure by Letters Patent:

1. A window provided with a window frame and a sash, center pivoted on the said frame, and having stop members interlocking with stop members of the said window frame to form a continuous joint, each stop member being tubular and approximately rectangular in shape.

2. A window provided with a window 40 frame and a sash, center pivoted on the said frame, the inward swinging portion of the sash interlocking with outside stop members of the window frame, and the outward swinging portion of the sash interlocking with inside stop members of the said window frame 45 each stop member being tubular and approximately rectangular in shape.

3. A window provided with a window frame and a sash for the same, the said frame and sash having interlocking tubular stop 50 members of an approximately rectangular cross section.

4. A window provided with a window frame and a sash for the same, the said frame and sash having interlocking tubular stop 55 members of an approximately rectangular cross section, and a pin in the joint between each stop member and the part of the frame or sash to which the stop member is secured.

5. A window provided with a window 60 frame and a sash for the same, the said frame and sash having interlocking tubular stop members of an approximately rectangular cross section, and packings fixed in the grooves in the faces of the interlocking stop 65 members of the sash and adapted to engage grooves in the faces of the interlocking stop members of the window frame.

6. A window comprising a window frame, a sash for the same, and center pivots for the 70 sash and retractably held therein, the pivots being adapted to engage bearings in the window frame.

7. A window comprising a window frame, a sash for the same, center pivots for the 75 sash and retractably held therein, the pivots being adapted to engage bearings in the window frame, and a locking device for the said sash to lock the latter in place on the window frame while retracting the said pivots.

8. A window comprising a window frame, a sash for the same, center pivots for the sash and retractably held therein, the pivots being adapted to engage bearings in the window frame, and clamping screws engaging the 85 pivots and the sash, to lock the pivots in either an extended or retracted position.

In testimony whereof I have signed my name to this specification in the presence of two subscribing witnesses.

SIDNEY U. BARR.
